US00D903611S

(12) **United States Design Patent** (10) Patent No.: **US D903,611 S**
Sannai et al. (45) Date of Patent: ** Dec. 1, 2020

(54) **SEMICONDUCTOR DEVICE**

(71) Applicant: **Mitsubishi Electric Corporation**,
Tokyo (JP)

(72) Inventors: **Hiroya Sannai**, Tokyo (JP); **Tatsuya Kawase**, Tokyo (JP); **Seiichiro Inokuchi**, Tokyo (JP); **Naoki Higashikawa**, Kariya (JP)

(73) Assignee: **Mitsubishi Electric Corporation**,
Tokyo (JP)

(**) Term: **15 Years**

(21) Appl. No.: **29/697,804**

(22) Filed: **Jul. 11, 2019**

(30) **Foreign Application Priority Data**

Mar. 29, 2019 (JP) 2019-006781

(51) LOC (12) Cl. **13-03**

CLAIM

The ornamental design for a semiconductor device, as shown and described.

DESCRIPTION

FIG. 1 is a front, top and right side perspective view of a semiconductor device showing our new design;

FIG. 2 is a rear, bottom and left side perspective view thereof;

FIG. 3 is a front view thereof;

FIG. 4 is a rear view thereof;

FIG. 5 is a top view thereof;

FIG. 6 is a bottom view thereof;

(Continued)

FIG. 7 is a right side view thereof; and,
FIG. 8 is a left side view thereof.

1 Claim, 8 Drawing Sheets
